UNITED STATES PATENT OFFICE

EDWARD W. BUEHL, OF CHICAGO, ILLINOIS.

DESIGN FOR A COAT-FORM.

SPECIFICATION forming part of Design No. 24,076, dated March 5, 1895.

Application filed April 2, 1894. Serial No. 506,128. Term of patent 7 years.

To all whom it may concern:

Be it known that I, EDWARD W. BUEHL, a citizen of the United States of America, residing at Chicago, in the county of Cook and State of Illinois, have invented a new Design 5 for a Coat-Form, of which the following is a specification.

My invention relates to a certain design for a coat form illustrated in the accompanying drawings by means of three figures, of which—

Figure 1 is a side view of the same; Fig. 2, an edge view, and Fig. 3, a top view.

Said form consists of a body, A, the rear edge of which is substantially straight and the front edge of which is convex, said edges being united at the top by a curved outline. The bottom edge of the form is shown as straight, but the shape of the same is not material. From the margin the form curves up-

ward, the portion of said curve marked a , being less convex than the other portions and terminating in a rounded knob, a' , near the top and rear portions of the form. The other portions of the curved margin are more convex and are connected with said knob by a reverse curve, a^2 .

The essential portions of my invention are the substantially straight back, the convex front and top and raised knob, a' , and the reverse curve, a^2 .

I claim as new and desire to secure by Letters Patent—

The design for a coat form herein shown and described.

EDW. W. BUEHL.
